UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

WOODEN SINGLE-SHEATHED BOX-CAR.

1,244,809.

Specification of Letters Patent.

Patented Oct. 30, 1917.

Application filed August 15, 1916. Serial No. 115,021.

To all whom it may concern:

Be it known that I, JACOB H. WEISBROD, residing at St. Louis, Missouri, and being a citizen of the United States, have invented certain new and useful Improvements in Wooden Single-Sheathed Box-Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Figure 1 is a composite view, the upper left-hand quarter being a horizontal section through the car body showing the flooring in place; the lower left-hand quarter showing the underframe in plan; the upper right-hand quarter disclosing the roof-framing, and the lower right-hand quarter illustrating the roof in plan;

25 Fig. 2 is another composite view depicting on the left a vertical longitudinal longitudinal section of the car and on the right showing the car in side elevation;

30 Fig. 3 illustrates left and right transverse vertical half-sections, said sections being taken on the lines 3—3 and 3a—3a, respectively, of Fig. 2;

35 Fig. 4 is an end elevation of the car showing the end and corner posts and end plate stiffener;

40 Fig. 5 is a vertical section through the side wall of the car, intermediate portions being broken away, the section being taken at the posts;

45 Fig. 6 is a similar section taken between the caps and shoes for the posts and braces;

Fig. 7 is a detail horizontal section through the corner posts, being taken on the line 7—7 of Fig. 4.

In the present invention, the production 50 of a car principally composed of wood is contemplated, which car shall have the advantages of the single-sheathed car that is provided with steel framing for the super-

structure, but in which the reduction in the use of steel materially lessens the cost of 55 manufacture.

The avoidance of the lack of proper connection of the posts and braces of the superstructure to the plates, sill and walls is accomplished, with the result that the joints 60 between these elements are kept closed and are water-tight.

Prevention of the lodgment of water, due to rain or other causes, in the joints between the walls and the plates and sills, together 65 with means for draining water from such joints as are not likely to readily free themselves of liquid accumulations, is simply and satisfactorily attained.

The importance of this feature is not inconsiderable, as decay of the wood at the joints is thereby prevented.

An assembly of framing members, walls and flooring is had which preserves the walls in perfect alinement, obviating the tendency 75 of the posts and braces of the framing to bulge outwardly under the influence of loading, which eliminates the opening of the seams between the wall boards, frequently 80 noticeable in wooden cars.

In the car illustrated, and which embodies the invention, 13 represents the side sills and 12 the side plates of the car. Suitably spaced longitudinally of the side sills 13 and side plates 12, are vertical side posts 85 19 between which are arranged diagonal braces 20. The lower ends of side posts 19 and braces 20 are seated in metallic shoes 16a mounted upon the side sills 13. Surmounting the upper terminals of said side 90 posts and braces, are metallic caps 16 appropriately positioned along the under sides of the side plates 12. Sill and plate rods 21, some vertically and some obliquely arranged, assist in holding the side-framing 95 members in proper relation, which members, it is seen, constitute a truss wherein the side plate is the top chord and the side sill is the bottom chord.

The car is of the single sheathed type and 100 the side walls 11 comprise horizontally disposed boards assembled one above the other, which boards have tongue and groove connections as indicated at 22 in Figs. 5 and 6. The side plates 12 and side sills 13 are rabbed at 10 and 10a, respectively, on the 105

inner sides of side plates and sills and to a greater depth than the thickness of the boards forming the side walls 11.

The inner faces of the side walls 11 are arranged to be flush with the similar faces of the side plates 12, in consequence of which the outer faces of the top and bottom boards of the walls 11 are spaced from the vertical faces of the rabbeted portions in side plates 12 and side sills 13, thereby creating air spaces 14 between the outer upper edge of walls 11 and side plates 12, and the lower outer face of walls 11 and the vertical faces of the rabbeted portions of the side sills 13. Said air spaces 14 extend longitudinally of the car substantially from the corner posts at one end to those at the other. Shoes 16^a and caps 16 are provided with flanges 15^a and 15, respectively, which occupy and fill the spaces 14 where said shoes and caps are present. Said flanges 15 and 15^a, therefore, form backing between the side walls and the side plates and side sills at these points. Caps 16 and shoes 16^a are provided with pockets into which the terminals of posts 19 and braces 20 are fitted, the ends of said posts and braces being reduced to enter the pockets, the inner faces of the side posts and braces being adapted to lie in contact with the boards of walls 11, which boards are suitably bolted or otherwise fastened to said side posts 19 and braces 20. Fitted into the angles between the under-sides of the side plates and the top boards of walls 11, are beveled strips 17 which extend between successive caps 16 and close the bottom of the air spaces 14 paralleling the side plates 12. Similar beveled strips 17 are likewise arranged to fit into the angles between the bottom boards of walls 11 and the upper surfaces of side sills 13, said lower beveled strips extending between the shoes 16^a and closing the lower air spaces 14 at the car sides. In each car side the bottom board of wall 11 is rabbeted and the outer board of floor 29 is let into the rabbet here formed, said floor board lying on top of sill 13. In the illustrated form, the sills 13 extend under the outer floor boards 29 inwardly beyond the inner face of walls 11. The bottom boards of the side walls are, therefore, firmly positioned between the flanges 15^a of shoes 16^a and the edges of floor boards 29, very definitely positioning the lower end of walls 11.

Because of the letting in of the side walls 11 into the rabbeted portions of the side plates 12 and side sills 13 and the bearings which the upper and lower edges of walls 11 have against the flanges 15 and 15^a of the caps and shoes, respectively, together with the interlocking of the bottom side wall boards with the floor boards 29, and also because of the tongue and groove connections between the superposed boards of the

side walls, a very rigid side wall is formed and the parts thereof so correlated that the resistance of the side plates and side sills to the bulging of the boards is transmitted throughout the area of side walls 11, maintaining such walls in perfect alignment. The walls 11, therefore, resist bulging due to the influence of lading, and consequently the relief from the stress of bulging side walls against the side posts and braces, keeps the side truss organization unimpaired. It is therefore seen that the design is such that greater strength is present in the side wall construction than has been common heretofore and without the employment of a greater amount of material to provide the resistive properties.

In addition to the inherent strength of the side wall construction, the latter also is possessed of water-tight qualities. In ordinary joints where at the line of severance the elements of the joints are in continuous contact, the application of water to said joints is very apt to permit the passage of the water from one side of the joint to the other. This is avoided in the wall construction of the car herein disclosed. When in perfect condition there is little likelihood of water, resulting from rain or other causes, being driven into the joints in such manner that it will follow the path of severance of the elements of the joints at the side plates and side sills. If, however, after considerable service the wood of the car tends to become to any degree warped, protection against a communication from the interior of the car to the outside atmosphere, which will be sufficient to allow water to work into the car, is still present by reason of the air spaces 14 which break the joints between the sills, plates, walls and beveled strips of the wall construction. Assuming that water may enter between the side plates and strips 17, or side sills and lower strips 17, it will be unable to pass the air spaces 14, and consequently cannot pass between the upper or bottom boards of the walls 11 and the side plates 12 and sills 13 to find its way to the car interior. Moreover, any film of water which may work itself between the side plates 12 and upper strips 17, or the side sills 13 and lower strips 17, will not be retained long enough for it to do any damage to the joints. The construction is such that so little water may be present that the joints will be subject to rapid drying, thereby preventing the wood decaying at the joints.

It being more difficult for any water working between the lower strips 17 and the upper surfaces of side sills 13 to discharge itself, drainage passages 18 are drilled vertically through the side sills 13 and communicate with the lower air spaces 14, from which any accumulations of water will immediately pass out of the car side wall and

be discharged to the ground. Side walls 11 have strong connection with the end walls 28 of the car, as best disclosed in Fig. 7, where the corner posts 30 are shown to be in the form of pressings of angular cross-section. Each corner post 30 is provided with an outstanding flange 31 projecting from the side wall 11 and another outstanding flange 32 extending away from the end wall 28. The angle-shaped web of corner post 30 is connected to the side and end walls 11 and 28 by bolts 33 passing through the former, and bolts 34 extending through the latter. A ladder cripple 25 has a face 15 lying against the outer surface of wall 11 and another face lying against flange 31 of corner post 30, said ladder cripple 25 being secured in place by bolts 26 passing through it and flange 31 of the corner post 20 and other bolts 27 passing through said ladder cripple and side wall 11. Ladder rounds 23 may have their outer ends secured to cripple post 25. As shown in Fig. 7, the end grab iron 24 may have one of its ends 25 riveted to the flange 32 of corner post 30.

It is manifest that I have constructed a strong side wall which is securely and firmly combined with the end walls 28 of the car, which side wall preserves its vertical alignment and relieves the side framing from undue stress, whereby the truss formation of the side-framing is protected from distortion and, consequently, is relatively stronger than in ordinary wood constructions. It is also obvious that I have protected the interior of the car from invasion by water.

The ends of the car have been shown as of conventional construction, but it is, of course, to be understood that the construction of the side walls may be embodied in the end walls whenever this is desirable.

Also, when it is not convenient to press the corner post 30 as illustrated and described, its substantial equivalent may be secured by using a commercial Z-bar and riveting thereto a standard angle.

What I claim is:

1. In combination in a car wall, a sheathing, a sill and a top plate rabbeted to a depth greater than the width of said sheathing, said sheathing being positioned in the rabbets of said sill and plate to form air spaces between the last two mentioned elements and said sheathing, closures for the air spaces and truss elements combined with said sill and plate.

2. In combination in a car wall, a truss having top and bottom chords which are rabbeted, a sheathing positioned to have its upper and lower edges within the rabbets, means forming air spaces between said chords and sheathing, and members coöperating with said truss and sheathing to close said air spaces.

3. In combination in a car wall, a truss having top and bottom chords and posts, a sheathing comprising mutually stiffening sections, the outer face of said sheathing engaging said posts but not said top and bottom chords, and means so coöperating with said truss and sheathing that flexure of the latter is resisted by its coöperation with said top and bottom chords to minimize its lateral pressure on said posts. 70

4. In combination in a car wall, framing comprising a sill and a plate, each longitudinally rabbeted and stress members interposed therebetween, a sheathing having marginal portions in the rabbets of said sill and plate, and connectors joining said stress members to said sill and plate and spacing faces of said marginal sheathing portions from the last two mentioned elements. 75

5. In combination in a car wall, framing comprising a sill, and a plate and stress members interposed therebetween, a sheathing lapping said sill and plate and having a face contacting with said members and spaced from said sill and plate, and longitudinal space-closing members, the arrangement of the parts forming internal spaces adjacent said sill and plate. 80

6. In combination in a car wall, framing comprising a sill and a plate and stress members interposed therebetween, a sheathing inset in said sill and plate in correlation therewith to resist bulging and being provided with a face contacting with said members and spaced from said sill and plate, and connectors joining said members with said sill and plate and extending between the last two mentioned elements and said sheathing. 95

7. In combination in a car wall, a sill and a plate provided with rabbets having horizontal and vertical faces, stress members of less width than said sill and plate interposed between the same, a sheathing substantially 100 equal in height to the space between the horizontal rabbet faces of said sill and plate set into said rabbets and being of less width than the depth of the latter, and shoes and caps embracing terminals of said members 105 and having portions lying against the vertical rabbet faces of said sill and plate, forming backing for said sheathing and spacing the same from the vertical rabbet faces. 110

8. In combination in a car wall, a top 120 plate provided with a rabbet having horizontal and vertical faces, a sheathing of less width than the depth of the rabbet having an edge in contact with the horizontal rabbet face and a margin of one of its 125 faces spaced from the vertical rabbet face and forming an air channel therewith, truss panel members to which said sheathing is attached, caps embracing terminal portions of said members and having por- 130

- tions projecting into and interrupting said air channel, and strips contacting with said sheathing and plate and closing the uninterrupted air channel portions.
5. 9. In combination in a car, a wall comprising a sill provided with a rabbet having horizontal and vertical faces, truss panel members, pocketed shoes receiving end portions of said members and having portions 10 lying against the vertical rabbet face, a sheathing secured to said members, lapping said shoes and forming an intermittent channel with the latter and the vertical face of the sill rabbet, said sheathing having a 15 lower rabbeted edge and a floor projecting into the sheathing rabbet and resting upon the horizontal face of said sill rabbet.
10. In combination in a car wall, a top plate provided with a rabbet, a sheathing of 20 less width than the depth of the rabbet having a marginal portion positioned in the latter, posts and braces to which the sheathing is secured, caps positioned along said plate receiving the post and brace terminals 25 and provided with flanges laterally spacing said plate and marginal sheathing portion, and strips extending between the caps, the parts being arranged to form an intermittent interval air space adjacent said plate.
30. 11. In combination in a car wall, a longitudinal framing member, a sheathing having a marginal portion inset in said member, posts and braces to which said sheathing is secured, connectors combining said 35 posts, braces and member and forming abutments for said sheathing, and strips extending between said connectors, the parts forming a joint having an internal air chamber and being in surface contact outside said 40 chamber.
12. In combination in a car wall, a longitudinal framing member, a sheathing having a marginal portion inset in said member, posts and braces to which said sheathing is secured, connectors combining said posts, 45 braces and member and forming abutments for said sheathing, and strips extending between said connectors, the parts forming a joint having an internal air chamber and being in surface contact outside said chamber, there being drainage passages from the latter to the exterior.
13. In combination in a car, a framing comprising a sill, a plate, posts and braces, and connectors combining the same, a single 50 sheathing comprising mutually stiffening sections, a floor rabbeted into said sheathing, the latter being rabbeted into said sill and plate, said connectors spacing a face of said sheathing from faces of said sill and plate, 55 and means closing openings to the spaces so formed at the sill and the plate, whereby the interfitting parts at each of the last two mentioned elements forms a joint containing an air chamber.
14. In combination in a car, a framing member having a longitudinal rabbet, a sheathing fitted into the rabbet and other members combined with said framing member and sheathing, the elements being arranged to form an internal air space and having joint-forming portions in surface contact except at said space.

In witness whereof I have hereunto set my hand in the presence of two witnesses.

JACOB H. WEISBROD.
